**ANCHOR HANDLING PIVOTALLY TRAVERSING
HOIST**

Mark O. Whitney, 55 Broad St., Matawan, N.J.

Filed Dec. 16, 1953, Ser. No. 398,528

8 Claims. (Cl. 114—210)

This invention relates to an anchor weighing or hoisting device as well as a casting or launching device and, more particularly, to an anchor winch and vertically swinging anchor support for raising the anchor out of the water by the helmsman from a point remote from the hoisting device.

This invention is an improvement over, and therefore related to, my Patent No. 2,333,836, issued November 9, 1943.

The prior patent illustrates a deck anchor hoist which in substance is similar to the present invention; however, the present invention provides additional features such as a guiding device on the transversing arm to position the anchor in a predetermined position before lifting and placing the anchor on the deck. Also, there is provided a cooperating lock or retaining means on the deck so that when the anchor is deposited on the deck, it will automatically slide into a locked or rigidly retained position. Likewise also, the prior patent illustrates only a deck anchor hoist. The present invention pertains to any anchor hoist whether mounted on a deck or otherwise and, in addition, contemplates further embodiments of the hoist whether applied to raising an anchor or to the raising of any load where the same circumstances exist.

It is an objective of this invention to provide an anchor hoist in which a load supporting arm extends out from the hull of the boat to lift the anchor clear of the boat and in which the anchor supporting arm swings in a horizontal movement to carry the anchor onto the deck of the boat.

It is a further objective of this invention to provide an anchor hoist in which a load supporting arm extends out from the hull of the boat to lift the anchor clear of the boat and in which the anchor supporting arm is provided with a shelving seat to position the anchor in a predetermined position with relation to the arm as the supporting arm swings in a horizontal movement to carry the anchor onto the deck of the boat.

A still further objective of this invention is to provide an anchor hoist in which a load supporting arm extends out from the hull of the boat to lift the anchor clear of the boat and in which the anchor supporting arm swings in a horizontal movement to carry the anchor onto the deck of the boat, and in which the deck of the boat is provided with a guiding and retaining means for automatically positioning and locking the anchor in a rigidly retained position.

A further objective of this invention is to provide a hoist in which a load supporting arm extends out from the hoist to lift a load clear of the supporting structure for the hoist and in which the load supporting arm swings in a horizontal movement to carry the load onto the supporting structure.

2

A still further object of this invention is to provide a hoist in which a load supporting arm extends out from the hoist supporting structure and in which the load supporting arm is provided with a guiding means to position the load in a predetermined position with relation to the arm before the supporting arm swings in a horizontal movement to carry the load onto the supporting structure.

Further objectives of this invention shall be apparent by reference to the accompanying detailed description and the drawings in which

Fig. 1 is a side elevational view of the anchor hoist in a retracted position with the anchor deposited and locked in a stored position,

Fig. 2 is a side elevational view with the hoisting arm extended and the anchor suspended therefrom,

Fig. 3 is a plan view of the anchor hoist taken on line 3—3 of Fig. 2,

Fig. 4 is a cross sectional view taken on line 4—4 of Fig. 2,

Fig. 5 is an end elevational view taken on line 5—5 of Fig. 2,

Fig. 6 is a schematic illustration in elevation of the further embodiment of the hoist,

Fig. 7 is a front elevational view taken on line 7—7 of Fig. 6,

Fig. 8 is an enlarged detailed view of the hoist mechanism shown in Fig. 6,

Fig. 9 is a plan view taken on line 9—9 of Fig. 8, and

Fig. 10 is a detailed view of the stop arms and the coupling arms.

Referring to the drawings and particularly Figs. 1 and 2, there is illustrated in dotted lines the bow 5 of the boat and the deck 6 of the boat. The device to be described mounts directly on the deck 6 by means of a deck plate 7 which may be securely fastened in the usual manner by bolting thereto. The hoisting mechanism 4 is mounted to the deck plate 7. The hoisting mechanism consists of a hoisting arm 8 which is in turn secured to a journal or axle 9 mounted in bearings 10, the bearings 10 being secured to the deck plate 7. The journal or axle 9 extends through a hole 10A in the arm 8 and is pinned or keyed to be retained in this position. A pair of parallel cheek pieces 11 rise from opposite edges of the arm 8 and are therefore in spaced relation. These cheek pieces may be formed integral with the arm or separately therefrom and secured to the arm. One of the purposes of the cheek pieces is to form a housing to support sheaves 12 and 13. The arm 8 at its opposite end is provided with a hood 16, the hood 16 being similarly constructed with a pair of parallel extended cheeks 16A and 16B (Figs. 1, 2 and 5). These cheeks in turn support a sheave 17. Also mounted between cheeks 16A and 16B are a pair of arcuate shaped seats M and N. Seats M and N are affixed to cheeks 16A and 16B respectively.

An anchor locking device 18 is secured to the deck as illustrated in Figs. 2 and 3. The device 18 is comprised of two supports 18A and 18B (Fig. 3). Each support is provided with a hook shaped end 18C to receive the end of the anchor when the anchor is in its retracted locked position (Fig. 1). A pair of coupling arms 20 are pivotally mounted on the journal 9 on opposite sides of the cheek pieces 11 (Fig. 4). These arms extend through an opening "X" (Fig. 3) in the deck plate. On the opposite ends of arms 20 a sheave 21 is mounted by means of a bearing rod 21A. Each arm 20 is provided with a circular end 21B serving as a cam and into which are provided a pair of notches 20A and 20B, the notches 20B being in

65

alignment with each other and the notches 20A being in alignment with each other. The notches 20B are provided so that a pair of pivotally supported stop arms 1 will abut with arms 20 when arms are in the position illustrated in Fig. 2. In this position the ends 1A will fit into the notches 20B. It is apparent that arms 1 must be pivotally supported at 2 on either side of the cheek pieces 11 (Fig. 4) and must lie in the same plane with arms 20. Arms 1 are provided with a cam face 1B which bears upon a pin 57 one end of the cam face is flat and positioned tangential to pin 57 to allow pin 57 to move into or out of an abutting relationship. It is also to be remembered that due to the weight of the upper portion of arms 1, when pin 57 moves counter-clockwise the cam portion of arms 1 drops by gravity disengaging the end 1A of each arm from notches 20B. Pin 57 is shown without a roller, however it may also be provided with a roller contact. Therefore there are a pair of pins 57, each one extending from the outer face of each cheek 11 in the position as illustrated in Figs. 1, 2 and 4. With the arm 8 in its extended position (Fig. 2), arms 1 will be retained as illustrated and arms 1 will in turn act as a stop for arms 20, thus supporting sheave 21 in the position illustrated. When arm 8 is raised, pin 57 moves pivotally about 9, when pin 57 moves away from the flat face of arm 1, arm 1 will move clockwise as shown in Fig. 10. With arm 8 in the position shown in Fig. 10, pin 57 will bear against the cam face 1B of arm 1 and the lower end of arm 1 will bear against the roller or cam 21B. It is to be noted in Fig. 4 that the bearing rod 21A also supports a pair of cams 21B. The cams 21B are mounted to align with arms 1. Referring back to Fig. 10 it is apparent that after arm 8 is moved to the position shown in Fig. 1 and then moves clockwise to this position as arm 8 and cheek pieces 11 move clockwise there is a lifting leverage exerted by pin 57 on cam face 1B moving arm 1 counter-clockwise so that there is a counter-clockwise cam action pressure of the lower end of arm 1, bearing against the cam 21B, which will cause 21B and arm 20 to pivotally move counter-clockwise until 1A of arm 1 has moved into the notches 20B as shown in Fig. 2. During this operation the cable is being payed out, allowing arm 20 due to release of cable pressure to move downward by the force of gravity. This downward movement of the arm 20 moves arm 20 counter-clockwise sufficiently to give the necessary distance or leverage when raising arm 8 clockwise, to thus throw arm 8 past the vertical position. From this position arm 8 will continue to travel due to the force of gravity. It is to be further noted that in raising arm 8 from the position illustrated in Fig. 2 to the vertical position, it is necessary to take in cable 15 to effect this raising of the arm. However, when arm 8 passes the vertical position, cable 15 is payed out and arm 8 descends by gravity in a counter-clockwise direction toward the deck. During this descent pivot 57 will contact 20A of arm 20, thus also moving arm 20 in a counter-clockwise direction. It is evident that as arm 20 (see Fig. 2) moves counter-clockwise and arm 1 remains stationary as to pin 2, notch 20B will withdraw from 1A of arm 1 and arm 1 by force of gravity will drop to a position as shown in Fig. 1. It is to be further noted that even when arm 8 is extended to its extreme position pin 57 will retain arm 1 in the position illustrated in Fig. 2. Even when arm 20 drops away from arm 1 by gravity as the cable 15 is payed out, the mute cable 15 is again taken in, arm 20 will return to the position illustrated in Fig. 2. It is apparent that a cable 15 may be passed over sheave 17 mounted in hood 16 and over sheaves 13 and 12 mounted in the cheek pieces 11 and downward and around sheave 21 and back over a fixed sheave 60 (not a part of the invention) mounted under the deck of the boat. The cable in turn will pass to a drum or hoisting device (not shown) to be retracted when the anchor and hoist are to be raised or to be payed out when the hoist is

extended and the anchor dropped. Referring to Figs. 2 and 5, it is to be noted that the hood structure 16 supporting the sheave 17 is constructed so that the parallel cheeks 16A and 16B on their inner surface are provided with cam shaped areas 38 and 39. These cam shaped areas and also seat M are rounded off as illustrated in Fig. 5 so that the upper end 37 of the anchor 33 will abut with the cam surfaces 38 and 39. The surfaces 38 and 39 will guide the anchor to turn it into an aligned position (Fig. 5) so that the parallel faces 35 of the end 37 will align with and fit into the inner parallel faces of the cheeks 16A and 16B. It is to be noted that the end 37 of the anchor 33 must be wider between faces A and B (Fig. 2) than it is between faces C and D (Fig. 5) and, in addition, the distance C—D must be slightly less than the distance E—F. Thus if the anchor end 37 should abut with the hood 16 in the position illustrated in Fig. 2, since the distance A—B is greater than E—F, the upper end will abut with the cam surfaces 38 and 39. Since the end 37 cannot enter between the inner faces of hood 16 in this position, the rounded surfaces of the end 37 will ride against the rounded surfaces of 38 and 39 and twist end 37 until it assumes the position of Fig. 5, when it will enter between the cheek pieces 16A and 16B. It is apparent that with this arrangement the anchor 33 when hoisted or lifted to its abutment with hood 16 must be positioned as described. This is essential as the lower pivotal end of the anchor supporting the extended prongs 33A must be in the position illustrated in Fig. 2 (or in a parallel position to the retracted position of Fig. 1) before arm 8 begins its traverse from the extended position of Fig. 2 to the retracted position of Fig. 1. It is apparent that due to the pivotal mounting of the end 33A the prongs 33A may be in an opposite position, that is to the right of the main portion 33 and, of course, when the anchor is abutting with sheave 17 and arm 8 begins its traverse as soon as the anchor 33 reaches a position to the left of vertical at a predetermined position, the prongs 33A will drop by gravity to the left of the main portion 33. Referring to Fig. 1 it is apparent that when the anchor 33 has been raised into a predetermined position with the end 37 registered in the hood 16, the cable 15 when further retracted will naturally exert a lifting pressure on hood 16 and sheave 17. Since end 37 cannot travel any further, arm 8 will be pulled upward due to the pull over sheave 13 and the pivotal mounting 9. Arm 8 travels as indicated by the dotted lines of Fig. 1 and, of course, the cheeks 11 will pass through the opening "X" in the deck plate and pins 57 will abut with the notches 20A of arms 20 and thus carry arms 20 in a counter-clockwise direction to the extreme position illustrated in Fig. 1. It is to be noted that cable 15 in the position illustrated in Fig. 1 would abut with the edge of the opening "X". Therefore to prevent the cable from chafing on this edge, a roller "Y" is mounted across the edge of the opening to prevent the cable from chafing thereon. It is also to be noted that cable 15 in its retracted position passes over sheave 13 and from sheave 13 goes directly to sheave 21. However, when the arm 8 is again extended, cable 15 will automatically pass from sheave 13 onto sheave 12 when sheave 12 has passed arm 20. It is also apparent that the pull of cable 15 on sheave 21 will pull arms 20 in a clockwise direction to in turn carry arm 8 in a clockwise direction when extending arm 8. The operation of retracting anchor 33 consists of taking in cable 15 on a hoist or drum (not shown) which retracts anchor 33 out of the water and into an abutting relationship with hood 16. The continued retraction of cable 15 causes the hoist to pivotally move about 9. When arm 8 reaches a position to the left of a vertical from 9, cable 15 must be reversed in its direction, that is, it must be payed out to allow arm 8 to drop by gravity until the arm and anchor reach their position on the deck. It is to be noted that in dropping arm 8 the extended prongs 33A of the anchor

will fall in a counter-clockwise direction and the end of the prongs will fall into a registering position in the mouth of the hook shaped portion 18C of the locking elements 18. As the arm 8 drops further, the ends of the prongs 33A will slide inward into the hook shaped portion 18C (due to their pivotal mounting) and, of course, in a fully retracted position, the prongs are in a tightly registered locked relationship with elements 18. Referring to Figs. 1 and 5, it is to be noted that when the end 37 of the anchor 33 has been raised so that the end 37 has twisted and been drawn between the cheeks 16A and 16B, the end 37 will be retained in an abutting relationship with the sheave 17. When the hood 16 moves into the dotted position (Fig. 1) the lower shoulders of the end 37 of the anchor will ride on the seats M and as the arm 8 drops to the deck it is apparent that the end 37 will be locked or retained in hood 16 so that it cannot be moved to the right (Fig. 1), and since the ends 33A of the anchor are fitted into the hooked portion 18C the anchor cannot move to the left (Fig. 1). Thus the anchor is securely locked and retained in the position illustrated. It is to be further noted that in raising arm 8 back to the dotted position (Fig. 1) after arm 8 continues to travel in a clockwise direction, arm 8 will reach a position to the right of vertical wherein the anchor is suspended beyond the bow 5 of the boat. At this predetermined position the end 37 of the anchor will slide off the seats M and the anchor will then drop away from the hood 16 as illustrated in Fig. 2. Of course it is apparent that prongs 33A consist of a pair of parallel extended prongs to fall into an aligned relationship with elements 18. As a precaution when the hood 16 is in the retracted position as illustrated in Fig. 1, an additional snap lock 43 may be utilized to lock the hoisting arm and hood in the position illustrated. The snap lock 43 may be manually mounted by lifting the hook shaped end 43A and catching it over a pin 42 in the hood 16. Or, the snap lock 43 may be operated automatically, that is, pin 42 as it descends with hood 16 may ride against the end 43A of the snap lock depressing element 43 until pin 42 has passed the end 43A. By utilizing a spring 43B, the end 43A will snap upward and hook over pin 42 when hood 16 reaches its ultimate retracted position. When it is desired to raise hood 16 and arm 8, it is simply a matter of releasing the snap lock 43. Thus in operating the device in an opposite direction to drop anchor when the snap lock 43 is released, cable 15 is again retracted by the hoist or mechanism (not shown). The pull of cable 15 will be affected on sheave 21 as the anchor 33 and arm 8 are still in a locked position. Thus with the pull on sheave 21, arms 20 will be moved in a clockwise direction and prongs 33A will slide out from under the hooked portions 18C before anchor 33 is actually lifted. The movement of arms 20 thus affects the same movement of arm 8 since arms 20 are abutting with the pins 57 and by means of the cheek plates 11 will affect the raising of arm 8 and the hood 16 will travel as indicated by dotted lines in Fig. 1 until hood 16 reaches the vertical position above journal 9. As soon as hood 16 passes to the right of the vertical position, cable 15 must be reversed in its direction, that is, it must be payed out and arm 8 will continue to drop by gravity until it reaches the position illustrated in Fig. 2. It is to be noted that during this downward travel of arm 8, shoulders M prevent the anchor from dropping onto the deck until after it has cleared the bow of boat. Upon reaching this position, cable 15 will be payed out and anchor 33 will drop away from hood 16 and be lowered into the water as desired. It is to be noted in this anchor lowering or dropping action that as the line 15 is payed out (the speed of dropping or lowering may be controlled to prevent the anchor from pounding on the deck), arms 20 are moved in a counter-clockwise direction and as cheeks 11 move in a clockwise direction, pins 57 will pick up arms 1 and thus

the opposite ends of arms 1 will act as a stop for arms 20 to retain arms 20 in the position illustrated in Fig. 2. It is to be remembered that arms 20 and arm 8 are pivotally moveable about the journal 9. Thus in the lowering of arm 8 from the vertical when cable 15 is payed out there would be a tendency for arm 20 to drop but the greater weight on arm 8 will cause arm 20 to continue to move counter-clockwise until it reaches the position illustrated in Fig. 2. This is caused by the cam 10 action of arms 1 (as shown in Fig. 10). Referring to Fig. 4 there is illustrated a view partially in cross section which illustrates the relationship of cheeks 11 of arm 8 and the manner of mounting the sheaves 12 and 13. By utilizing blocks 12B and 13B on either side of the sheaves and affixing the blocks to the cheeks, the sheaves may be retained in a pivotally supported position as illustrated. However, it is not necessary to use blocks between the cheeks 11. A wider sheave may be utilized and likewise, although arms 20 are illustrated as perfectly straight, utilizing blocks on either side of sheave 21, arms 20 may be bent inward to dispense with blocks, but in any event the cams 21B must be retained in alignment with coupling arms 1. It is also apparent in Fig. 4 the manner in which arms 20 are pivotally mounted on the journal 9. It is further apparent how the arms 1 are supported by brackets 1C and 1D on either side of arms 1 to pivotally support arms 1 with pins or bearings 2. It is also apparent in Fig. 4 the manner in which sheave 21 is mounted in an aligned position with sheaves 12 and 13 and may be retained in this position by a pair of blocks retaining sheave 21 spaced from the supporting arms 20 and pivotally retained on a center axle 21A. There is also shown a tie rod 42 (Fig. 5) which prevents the cable from jumping out or leaving the sheave 17. The end 37 may be forged as one with the anchor stock or it may be made in two half sections and bolted together with a bolt P (Figs. 2 and 5). In either case a slot or recess shall be provided so that the cable 15 (which enters 37 through a hole H) may be knotted or otherwise enlarged to serve as a swivel to prevent the anchor from twisting the cable into a knotty condition. Referring to Figs. 6, 7, 8 and 9 there is illustrated a still further embodiment of this invention. The hoist is applied to an industrial use rather than a marine or boat mounting. In this embodiment the operation of the hoist is identical to the foregoing embodiment but there is a departure in the structure. The structure comprises a supporting framework 60 with a flat base 61. The base 61 may be provided with rollers 62 or larger wheels (not shown) so that the structure may be readily moved into a desired position and, of course, locked or chucked in the desired position. The framework 60 supports a pair of spaced angle elements 63 and 64. Elements 63 and 64 are provided with a pair of parallel supporting walls 65 and 66. The general structure of the hoist, that is arm 8A, is similar to arm 8 of the foregoing embodiment except that it is shaped differently and, in addition to the sheaves 17A, 13A and 12A, arm 8A also supports a sheave 67 and a roller 68 to assist in guiding cable 15A. A pair of arms 20A are similarly affixed with relation to arm 8A and pivotally supported by a journal 9A and abut with similar arms 1E so that the complete structure operates exactly as the structure described in the foregoing embodiment. The only variation is the fact that sheave 17A is mounted to one side of arm 8A and the cable passing over sheave 17A must pass around roller 68 and over sheave 67 before passing over the sheaves 13A and 12A. This offset mounting permits lifting a load such as L (Figs. 6 and 7). With the load L lifted to the position illustrated in Fig. 6, there is a stop element 69 on cable 15A preventing lifting the load any higher. With stop element 69 abutting with the sheave, the arm 8A will be pivotally moved as shown in Fig. 6 or raised to 90° or less as shown in Fig. 7 and

as described in the foregoing embodiment, and the load L may then be swung in an arc supported below sheave 17A. When the arm 8A has reached the position to left of vertical (as shown in dotted lines Fig. 6), cable 15A may be payed out and the load L will be dropped to the dotted position illustrated in Fig. 6. In this embodiment there is illustrated a load L supported by cable 15A and there is no necessity of moving the load L higher than the framework 60 or into any particular position. Therefore the manner of deflecting or registering the end of the load such as the anchor of the foregoing embodiment is not disclosed. It is to be understood, however, that in the event it is necessary to retain the load in a desired position, the same manner of guiding the upper end of the load into a registered position as that illustrated and described with relation to the end 37 of the anchor in the foregoing embodiment may be utilized.

Various changes may be made without departing from the spirit of this invention, that is, in the preferred embodiment although there is illustrated a hoist mounted on the deck of a boat, the hoist may be mounted on any deck or any platform or any flat area whether it be a boat, a barge, or even a wharf and the complete operation will be as already described. Likewise, although there is shown a particular type of anchor, it is apparent that the guiding means and the locking means may be varied to conform with the anchor or device that is to be lifted. The guiding means and locking means are only illustrated to accompany the preferred embodiment. It is also to be understood that in the other embodiment of this invention, although the hoist supporting structure retains the load on one side, it may be constructed to retain it on the opposite side or by providing a turntable Z (Figs. 6 and 7). The whole supporting hoist may be rotated so that it may be utilized in a variety of positions rather than in a set position as illustrated. Similarly, although there is illustrated an arm 8A of a solid framework, the arm 8A may be of any desired length and may be comprised of a plurality of elements such as the usual boom of a hoist. This invention shall be limited only by the appended claims.

What is claimed is:

1. In combination with a deck anchor hoist including a hoisting arm pivotally mounted on a boat deck, means at the outer end of said arm to support a hoisting cable, means at the opposite end of said arm and carried by said arm for support of said cable, said means spaced from the pivotal center of said arm, a pair of coupling arms mounted adjacent to the pivotal end of said hoisting arm and pivotally moved with the movement of said hoisting arm, means carried by said coupling arms at their outer end for the support of a cable, a hoisting cable extending from the end of said hoisting arm about all of said supports for the hoisting of an anchor, an anchor secured to the outer end of said cable, a pair of stop arms, one on each side of said hoisting arm and pivotally mounted to said deck, said stop arms engaged by said hoisting arm to be pivotally moved into an engagement with said coupling arms for stopping the movement of said coupling arms and said hoisting arm when dropping said anchor, and said coupling arms engaged by said hoisting arm to release said stop arms from their locked position when said hoisting arm is elevated.

2. A deck anchor hoist including a pivotally mounted hoisting arm, a sheave at the outer end of said arm for support of a hoisting cable, cheek pieces secured at the pivotal end to opposite sides of said hoisting arm, cable sheaves mounted between said cheek pieces and spaced from the pivotal center of said hoisting arm, a pair of coupling arms mounted adjacent to the pivotal end of said hoisting arm to be pivotally moved with the movement of said hoisting arm, a sheave support for said cable at the outer end of said coupling arm, a hoisting cable extending from the end of said hoisting arm across the path of said cable sheaves and over the sheaves at the

end of said coupling arms, a pair of stop arms pivotally supported one on each side of said cheek pieces and said stop arms engaged by said cheek pieces to be pivotally moved into engagement with said coupling arms to stop the movement of said coupling arms during the dropping of said anchor and said stop arms being released from their engaged position when said hoisting arm is elevated.

3. In a device according to claim 2 in which there are a second pair of cheek pieces at the opposite end of the hoist arm and in which these cheek pieces are semi-circular in form and are rounded along the edge that will abut with the upper end of the anchor and are spaced apart enough to allow the anchor shaft to fit between the cheek pieces when the narrow portion of the anchor shaft is in alignment with the cheek pieces to thus turn and hold said anchor in a predetermined relationship with said deck, until the arm and anchor rest upon said deck.

4. In device according to claim 1 in which said cable may be retracted when said hoisting arm is fully extended, said anchor abutting with said hoisting arm during the retraction of said cable and said cable in turn raising said hoisting arm to a vertical position, a pair of pins mounted on either side of said hoisting arm and offset from the pivotal center of said hoisting arm, said pins abutting with said pair of pivotal arms to retain one cable sheave in an offset position, said position of said sheave providing a downward pull of said cable to lift said hoisting arm in its retracting motion, past its vertical position, and where it may be dropped toward the deck by the force of gravity.

5. A deck anchor hoist including a deck plate having an opening therethrough and bearings mounted on said plate at said opening, a hoisting arm and journals pivotally supported in said bearings, sheaves carried by said arm at its opposite ends for the support of a hoisting cable, a pair of coupling arms mounted adjacent to the pivotal end of said hoisting arm on said journals, said coupling arms pivotally moved with the movement of said hoisting arms, a sheave carried between said coupling arms at their outer end for the support of said hoisting cable, a hoisting cable extending about said cable sheaves, an anchor attached to the loose end of said cable, a pair of stop arms one on each side of said hoisting arm and pivotally mounted to said deck plate, said stop arms engaged by said hoisting arm when it is moved forward and lowered, said stop arms thus being pivotally moved into engagement with said coupling arms to thus position said coupling arms for the subsequent lifting of said anchor.

6. In a device according to claim 5 in which an anchoring positioning guide is mounted at the outer end of said hoisting arm to turn and hold said anchor in a predetermined relationship with said deck, means to first raise said anchor with said cable to abut with the outer end of said hoisting arm and be retained in a predetermined relationship, means to subsequently raise said hoisting arm with said cable in a pivotal movement until it has passed a perpendicular position, and means to drop said arm and said anchor toward said deck until the arm and anchor rest upon said deck in a particular position.

7. In a device according to claim 2 in which a pair of pins are mounted on opposite sides of said cheek pieces and offset above the pivotal center of said arm when in an extended position, each coupling arm provided with a cam positioned to align with and bear against the lower end of each stop arm, the upper ends of said stop arms bearing against said pins mounted in the opposed cheek pieces, the pressure from said coupling arms, when taken in cable, being translated to carry said hoist arm past the vertical position, and let the hoist arm and anchor drop by gravity to the deck.

8. In a device according to claim 5 in which a pair of

pins are mounted on opposite sides of said hoisting arm and off-set from the pivotal center of said arm, said coupling arms bearing against said pins when said anchor is in a retracted position, said hoist arm and anchor being first raised with said cable to a vertical position by taking in said cable, said coupling arms and said pins carrying said hoist arm in its pivotal movement past a vertical position when lifting said anchor off the deck until it reaches its maximum extended position, and then dropping the anchor away from said hoist arm.
